UNITED STATES PATENT OFFICE.

JESSIE JANE SHARP, OF CIRCLE, MONTANA.

SANITARY TOILET-SEAT PROTECTOR.

1,223,208.

Specification of Letters Patent. Patented Apr. 17, 1917.

Application filed January 15, 1916. Serial No. 72,234.

To all whom it may concern:

Be it known that I, JESSIE J. SHARP, a citizen of the United States, residing at Circle, in the county of Dawson and State of Montana, have invented certain new and useful Improvements in Sanitary Toilet-Seat Protectors; and I do hereby declare the following to be a full, clear, and exact description of the invention, such as will enable others skilled in the art to which it appertains to make and use the same.

This invention relates to new and useful improvements in sanitary toilet seat protectors and one of its objects is the provision of a device of this character, which shall be simple, durable and efficient and which may be manufactured and sold at a comparatively low cost.

A further object of this invention is the provision of a protector constructed of thin paper or other suitable material and cut to conform with the curvature of a toilet seat and which may be folded and sold from vending machines placed in convenient places within public stations or toilets used by the public.

A further and more specific object of this invention is the provision of metallic fastening means carried by the protector for detachably securing the protector to a toilet seat, which may be easily and quickly removed after being once used and another protector applied when desired.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawing, in which:—

Figure 1 is a front elevation of a toilet seat protector constructed in accordance with my invention;

Fig. 2 is a transverse sectional view of a toilet bowl and seat, illustrating my invention applied thereto;

Fig. 3 is a top plan view, illustrating the protector in a folded position, and

Fig. 4 is a fragmentary plan view of a portion of the protector and one of the

loops, illustrating the fastening means between the protector and one of the loops.

Referring in detail to the drawings, 1 indicates a toilet or flush bowl, having mounted thereon a seat 2 of any well known type, to which my invention is applied.

Referring specifically to my invention, the numeral 3 indicates a protector constructed of tissue or thin paper, which is of semi-circular formation and rests upon and entirely covers the top face of the toilet seat 2. Secured or formed integrally with the protector 3 is a pair of oppositely disposed flaps 4. The flaps 4 are each passed through the enlarged ends of loops 5 and bent rearwardly upon the protector 3. Reinforcing strips are provided with glue or other adhesive material 6 on one of their faces and are positioned upon the free ends of the flaps 4 and extended to points beyond, to provide extensions as illustrated at 7. The extensions 7 are attached to the protector 3, to firmly hold or secure the flaps 4 thereto, providing means for securing the loops 5 to the protector 3.

The loops 5 are each constructed of a continuous piece of wire having a reduced opening at the free ends thereof to receive studs 8, which are secured to the edges of the seat 2 in any suitable manner. It will be seen that the loops 5 may be easily and quickly attached and detached from the studs 8 to apply and remove the protector 3 as desired.

The protector 3 may be folded longitudinally and then transversely as illustrated in Fig. 3, to provide a compact article which may be placed in a vending machine in great numbers, so that protectors of this type may be furnished to the public by means of vending machines especially designed for articles of this kind.

While I have shown and described the preferred embodiment of my invention, it will be understood that minor changes in construction, combination and arrangement of parts may be made without departing from the spirit and scope of the invention as claimed.

Having thus described my invention, what I claim is:

A fastener for an article comprising a pair of oppositely disposed flaps formed on the article, loops provided with enlarged ends for receiving the flaps, and laterally pro-

jecting arms secured to the free ends of the flaps and extending from each side of the flaps and provided with adhesive material thereon, said flaps extending through the 5 loops and bent rearwardly upon the article and said arms being adhered to the article forming a hinge connection for the loops to the article and reinforcing the article at

points of the hinges of the loops to the article.

In testimony whereof I affix my signature in presence of two witnesses.

JESSIE JANE SHARP.

Witnesses:

R. A. SHARP,

ELIZABETH VERHULST.
